L. D. CHANDLER

FEED WATER REGULATOR

Filed Jan. 28, 1922

UNITED STATES PATENT OFFICE.

LEONARD D. CHANDLER, OF NORTH ABINGTON, MASSACHUSETTS.

FEED-WATER REGULATOR.

Application filed January 28, 1922. Serial No. 532,463.

This invention relates to automatic liquid feed regulators but more particularly to water feed regulators for boilers and the objects thereof will readily appear from the following specification taken in connection with the accompanying drawings of one embodiment of the invention which has been selected merely for the purposes of illustration.

10 Referring to the drawings:

Fig. 1 is a lay-out of the regulator showing the same applied to a boiler and connected parts thereof also the regulator valve being shown in section while other parts 15 are shown in elevation; and

Fig. 2 is a transverse section taken on the line 2—2 of Fig. 1 showing the water column and overflow pipe in section.

In the present exemplification a liquid 20 supply, herein a water pipe 1, is shown extending to and connected with a steam boiler 2, which latter may be of any well known type of boiler. Inserted in the pipe 1 is a valve casing 3 having inlet and discharge chambers 4 and 5 separated by a partition 6 having ports 7 and 8 providing communication between the inlet and discharge chambers 4 and 5 through different substantially parallel portions of said partition, these ports 7 and 8 being so arranged 25 as to discharge the liquid in substantially opposite directions into the discharge chamber 5 of said valve casing. A valve 9, preferably of the balanced type is arranged with in said valve casing to operate in conjunction 30 with said ports 7 and 8 substantially of the same area to regulate the flow of liquid from one chamber to the other of said valve casings. The valve 9 preferably comprises 35 a stem 10 upon which are two flanges 11 and 12 arranged to register respectively with the ports 7 and 8 and when in register with said ports, to substantially shut off the flow of 40 the liquid to said chamber 5.

45 The flanges 11 and 12 are connected together by a plurality of longitudinal ribs 13, 13 which slide through the ports 7 and 8 and having bearings in the two portions of said partitions 6 containing said ports.

50 The flanges 11 and 12 may have their faces 11' and 12' designed for various rates of flow per unit of lift of said valve flanges.

The pressure exerted axially of said valve by the water against the surfaces 11' and 12' will be counteracted by that acting in an 55 opposite direction against the flange 12' to the end that said valve will remain at the position in which it is placed, at least in so far as the forces of impact thereon by the water passing from the chamber 4 to the 60 chamber 5 is concerned. In other words the force exerted upon said valve will be balanced at any point in its throw.

Opposed to one end of the valve 9 is an adjustable stop screw 13' for positively 65 opening the valve when desired. From the opposite end of the valve 9 a stem 10 extends into an extension 14 of the valve casting 3 herein through a bearing in a partition 11'.

70 Within the extension 14 is a suitable diaphragm 15, herein formed in the shape of bellows preferably constructed of metal and attached at 16 to the valve stem 10, although it is to be understood that the invention is 75 not limited to the form of diaphragm shown. The bellows 15 has a peripheral flange 17 secured between two flanges 18 and 19, the flange 18 constituting a part of the extension 14 while the flange 19 constitutes a part 80 of a cap 20 which closes the end of said valve case extension. The diaphragm or bellows 15 serves as a partition to divide the interior of the extension 14 into two parts or chambers 21 and 22. The diaphragm 15 is inherently elastic or flexible to allow the valve 85 to move from its closed to its fully opened position and exerts a slight resilient action upon said valve preferably to close the same. To further act upon said valve, a spring 23 90 is provided, the latter being preferably arranged within said bellows between the end 16 that is attached to the valve stem and the cap 20 of said valve casing extension.

An adjusting screw 24 extending through 95 suitable packing or a leak-proof gland 25 is arranged to supply a predetermined degree of pressure upon said spring tending to close said valve.

The function of the valve 9 is to regulate 100 the flow of water or fluid, for it should be understood that the device is not limited to feeding of water, to a depository which may obviously be any reservoir or receptacle for

liquids wherein a predetermined or desired level is to be maintained. In the present example, as hereinafter stated, the said depository or receptacle is a steam boiler and in 5 such the water is desirably maintained at a certain level, which level is herein indicated by the line A—A.

This invention contemplates the production of means for maintaining the water in 10 said boiler at a substantially constant level but when this level is raised or lowered for one cause or another it is desirable that the valve 9 be closed or opened accordingly. When the level of the water in said boiler 15 reaches an abnormally high point the valve is preferably operated more quickly than it is during the ordinary operations of the boiler where the variations in said water level are but slight, at which time it is desirable that the movements of the valve 9 be 20 very gradual. To these ends the device is provided with two water columns 26 and 27, the column 26 being preferably attached to the boiler by two connecting pipes 28 and 29 arranged above and below said water line, and also having communication through pipes 30, 31, 32 and 33 with one side of the diaphragm, herein the chamber 22, although it will be obvious that the communication 25 30 between the column 26 and the chamber 22 need not be confined to the pipes 30, 31, 32 and 33 but that this communication may be effected through the main feed pipe 1 around the stem 10 of the valve 9, which 35 has more or less clearance, to the chamber 22.

The other water column 27 preferably has communication with the interior of the boiler 2 above the water level A preferably by means of a pipe 34 connecting the upper portion of the water column 26 with a chamber 43 intermediate the said water columns 26 and 27. The column 26 has communication at a point below its normal water level with said chamber 43 through a pipe 35. 40 45 The pipes 34 and 35 are provided with suitable valves 36, 36 wherewith to shut off communication between the two columns when necessary. The water column 27 has communication with the other side of the diaphragm 15 or herein the chamber 21 through pipes 37, 38, 39 and 40, the latter being herein connected with the cap 20 of said valve casing.

The head of water in the column 26 is 50 55 60 65 preferably adapted to remain substantially constant as it corresponds with the normal level of the water in the boiler 2, while the column 27 preferably contains a variable head, the normal level of which may, for example, be as indicated by the line B—B. These two heads, at the levels shown, act in such cooperation with the pressure exerted by the springs 23 and inherent resiliency of the diaphragm 15 that they maintain the valve 9 open sufficient only to meet the nor-

mal demands of the boiler and, under these conditions, maintain the level of water in said boiler, but a very small variation of these levels, be it ever so small, produces a difference in pressure within the diaphragm 70 or bellows 15 sufficient to move the valve in one direction or the other.

In the present example the difference in weight of the water in the water column 26 above that in the water column 27, as determined by the levels A and B is sufficient to counteract the action upon the valve 9 of the combined pressures exerted by the spring 23 and the diaphragm 15 tending to close said valve and maintain said valve open sufficient to supply the normal amount of water to the boiler. The maintaining of said valve in this position may be and herein is assisted by the peculiar inclinations of the faces 11' and 12' and of the lower flange 12² whereby the force of the water passing from the supply pipe through the ports 7 and 8 to the chamber 5 of the valve will be perfectly balanced and only the variations in the heads of the water in the two water columns cooperating with said spring and diaphragm, will have any tendency to change the position of said valve and at this point it should be understood that each unit of movement of the level of water in said column 27 has a definite unit of movement in the valve 9.

The normal supply of water to the boiler through the opening shown in the drawings will not be adequate to maintain the water in the boiler 2 at the level A—A when the boiler is subjected to an abnormal load and moreover when the burden upon said boiler is subnormal the normal supply of feed water through the valve as shown, will be too great. Hence the valve 9 must be operated to increase or diminish the flow of said feed water as the case may be.

It is desirable that the aforesaid change in the position of the valve 9 be very gradual under ordinary circumstances and to this end, means have been provided for very gradually replenishing the water in the water column 27 whereby its head will be increased sufficiently to assist the spring 23 and diaphragm 15 in overcoming the pressure of the head in the column 26 and thereby close or partly close said valve. Means also are provided for effecting a gradual discharge of the water in said column 27 whereby the head of water therein may be lowered and a reverse action of said valve to increase the supply of water to the boiler takes place. The means herein provided for replenishing said supply preferably include an overflow tube 42 connected with the upper end of the column 27, preferably arranged within the chamber 43, which chamber extends above and below the normal water level A—A of the boiler and has, as hereinbefore

stated, communication with the column 26, this chamber being separated from the said water column 27 by a partition 44 consisting of a tapered bushing 45 which surrounds 5 the overflow tube 42 and has screw-threaded engagement with a nipple 46, the latter having screw-threaded engagement with the lower end of the casing constituting the chamber 43.

10 By reason of the pipes 34 and 35 water from the column 26 and the boiler 2 is permitted to circulate freely through the chamber 43 and around the overflow tube 42, which latter is secured by the bushing 45 15 in a predetermined position to maintain the water in said boiler at the desired level. The tube 42 is provided with a restricted opening for taking care of the normal overflow of water from its surrounding chamber 20 and connecting tubes and directing said overflow into the column 27. For convenience the restricted opening is a slot 47 of any appropriate form arranged in the side of said tube 42 which slot, under normal 25 conditions, extends from a point 48 slightly below the line A—A to a point 49 above said water line but by reason of the adjustment hereinbefore described including the tapered bushing 45 and the nipple 46, the position 30 of said tube 42 may be varied when a different level of water is desired to be maintained.

In addition to the slot 47 which, in cross-section, is less than a full opening of the 35 tube 42, the upper end 50 of said tube is left open to its full extent constituting an auxiliary opening whereupon should the water in the boiler increase too rapidly, the size of the discharge opening will be augmented 40 by reason of the end opening 50 cooperating with the restricted opening 47 and, in such event, the head of water in the water column 27 will suddenly be increased and effect a 45 more rapid or abrupt movement of the valve 9 to close or partly close the ports 7 and 8 and cut off or reduce the supply.

The level B—B of water in the column 27 is, under normal conditions, maintained 50 substantially constant preferably in part by means of the discharge of water from said chamber 43 and in part by allowing said water to escape in predetermined quantities from said column 27 according to the normal amount that it is desired to have discharge through the overflow tube 42 from 55 the boiler. Obviously various forms of means may be provided for accomplishing this result but in the present example a needle valve 51 is arranged preferably near 60 the bottom of the column 27, said valve comprising a needle 52 cooperating with a tapered seat 53 in a partition 54 of said valve, said needle being appropriately mounted in a suitable casing so as to provide 65 for the fine adjustment of the opening there-

between and its seat, said needle being here- 70 in hand operated although the invention is not limited to this method of operation. Obviously the movements of the fluid in said column 27 may be made more or less responsive to the discharge of fluid through the slot 42 by increasing or decreasing the diameter of the pipe 37.

Within the scope and purpose of the invention the controlling valve 9 for said water supply may be placed at any convenient level with respect to the boiler but in view of the fact that the feed water pipes for boilers are generally above the boiler itself, the valve in the present example is shown at a higher level than the normal level of the water within the boiler and obviously where such is the case, the heads of water within the water columns 26 and 27 will have little effect upon the diaphragm 15 or bellows 15 without pressure of some sort being applied thereto. It is, therefore, partly for this reason that the pipes 28 and 34 are provided for connecting the several water columns with the boiler above the water line A and through these pipes, steam from the boiler 2 is admitted under equal pressure to both of said water columns, thereby to exert sufficient pressure to force the water therein upwardly respectively to the chambers 21 and 22 of the valve casing 3.

There are periods when the pressures upon opposite sides of the diaphragm 15, or in the chambers 21 and 22, may vary to such an extent that rupture of the diaphragm 15 is likely to occur. Therefore to protect said diaphragm in such an emergency, means are provided herein consisting of relief valves, preferably two 55 and 56 arranged respectively in bypasses 57 and 58 between the water columns 26 and 27. These relief valves, however, are arranged to work in opposite directions, for example, the relief valve 55 is adapted only to be opened by a pressure which is greater in the chamber 22 than it is in the chamber 21, thus acting in the direction of the arrow a while the valve 56 is adapted to be opened only when the pressure in the chamber 21 is greater than that in the chamber 22 and acting in the direction of the arrow b—said valves both being set to open when the pressure, as hereinbefore described, begins to approach, within predetermined safe limits, the bursting point of said diaphragm 15, thus preventing any injury to said diaphragm.

Due to the small opening 47 in the tube 42 through which the normal overflow must discharge to the column 27 and also of the needle valve 51, said opening and said needle valve are likely to become clogged by small particles of foreign substances, such as dirt or the like from the boiler or various sections of the apparatus, and therefore, means are provided herein consisting of a

screen 59 which surrounds the tube 42 and covers both openings 47 and 50 in said tube, thus keeping all such foreign matter away from direct contact with said overflow passages or openings. Obviously considerable water will be discharged through the valve 51 and if permitted to go to waste, would involve considerable expense. Therefore in the present example, means have been provided to return said waste water to the boiler. To this end a steam trap 60 is connected with the column 27 below the valve 51 and into this the water passes from said valve where it is brought in contact with steam supplied through appropriate means such as a pipe 61 from the boiler 2 or any other available source. The steam admitted through said pipe heats the water discharged from said column 27 and supplies a pressure at the discharge side of said needle valve substantially equal to that upon the other side thereof. Any appropriate means may be provided for conveying the water from said trap to the boiler but herein the water from said trap is first conveyed to a tank 62 from whence it is pumped by a suitable pump 63 through a pipe 64 back to said boiler.

By reason of the fact that the pressure within the steam trap 60 and at the discharge side of said needle valve is the same as that acting upon the water in the columns 26 and 27; or in other words equal to boiler pressure, the discharge of water from said water column 27 through the valve 51 will be less rapid than it would be if discharged at atmospheric pressure. Hence said valve 51 may be opened wider than would be possible in the latter case with much less likelihood of its clogging.

By reason of the two heads of water acting as described upon a diaphragm attached to a balanced valve in connection with a restricted and adjustable overflow and an adjustable discharge valve for the water column containing the variable head of water, a very delicately graduated operation or control of the feed water valve will be possible. Also the operation of the regulator will be more economical and less attention will be required by the attendant in charge, there being no stuffing boxes on the moving parts of the balanced valve to cause annoyance.

It should, however, be borne in mind that the apparatus, although shown as applied to a steam boiler, is not limited to such an application but may be utilized in feeding liquids of various sorts and although steam is used as a means for creating pressure in the two water columns obviously the invention is not limited to such but compressed air or other fluids are equally adapted to such a function. Furthermore, although one specific embodiment has been disclosed, it is to be understood that the specific terms employed are used in a generic and descriptive

sense and not for the purposes of limitation, the scope of the invention being set forth in the following claims.

Claims:

1. A feed water regulator comprising, in combination, a water supply, a valve for controlling said supply, and means for effecting a gradual movement of said valve to increase or diminish the flow of water from said supply, said means including an overflow pipe tube provided with a restricted fluid opening in the side thereof.

2. A feed water regulator comprising, in combination, a water supply, a valve for controlling said supply, and means for effecting a gradual movement of said valve to increase or diminish the flow of water from said supply, said means including an overflow tube provided with a restricted fluid opening for use under normal conditions, and an auxiliary fluid opening for use under abnormal conditions.

3. A feed water regulator comprising, in combination, a water supply, a balanced valve for controlling said supply, a diaphragm operatively connected with said valve, two water columns communicating respectively with spaces at opposite sides of said diaphragm, the level of the water in one of said columns being substantially constant, and means to convey surplus water therefrom to the other column including an overflow tube having a restricted opening to retard the flow of water to said second column.

4. A feed water regulator comprising, in combination, a water supply, a balanced valve for controlling said supply, a diaphragm operatively connected with said valve, two water columns communicating respectively with spaces at opposite sides of said diaphragm, the level of the water in one of said columns being substantially constant, means to convey surplus water therefrom to the other column including a tube having a restricted opening to retard the flow of water to said second column, and a screen covering said restricted opening to prevent foreign substances from clogging said opening.

5. A feed water regulator comprising, in combination, a valve, a diaphragm connected with said valve, a water column containing a substantially constant head of water having communication with one side of said diaphragm, a second water column containing a variable head of water supplied by overflow from said substantially constant head, and having communication with the other side of said diaphragm, and means to regulate the escape of water from said second water column.

6. A feed water regulator comprising, in combination, a valve, a diaphragm connected with said valve, a water column containing

a substantially constant head of water having communication with one side of said diaphragm, a second water column containing a variable head of water supplied by overflow from said substantially constant head and having communication with the other side of said diaphragm, the variations in the heads of said columns effecting movement of said diaphragm to open and close said valve, and means to regulate the escape of water from said variable column.

7. In a feed water regulator, a valve, a diaphragm connected with said valve, a water column containing a substantially constant head of water having communication with one side of said diaphragm, a second water column to contain a variable head of water supplied by overflow from said substantially constant head and having communication with the other side of said diaphragm, and a valve to regulate the escape of water from said second water column.

8. In a feed water regulator, a balanced valve, a diaphragm connected with said valve, a water column containing a substantially constant head of water having communication with one side of said diaphragm, a second water column to contain a variable head of water supplied by overflow from said substantially constant head and having communication with the other side of said diaphragm, and a needle valve to regulate the discharge of water from said second water column.

9. In a feed water regulator, a reservoir, a substantially balanced valve for controlling the supply of water to said reservoir, a diaphragm connected with said valve, a water column connected with said reservoir having a substantially constant head of water in direct communication with the water in said reservoir and also in communication with one side of said diaphragm, a second water column having communication with the other side of said diaphragm and having a variable head of water supplied by overflow from said reservoir, means to effect a restricted flow of water from said reservoir to said variable head to gradually move said diaphragm, and means to effect a variable discharge of water from said variable head.

10. In combination, a valve, a diaphragm, connected with said valve, a water column containing a substantially constant head of water having communication with one side of said diaphragm, a second water column containing a variable head of water supplied by overflow from said substantially constant head and having communication with the other side of said diaphragm, the variations in the head of said latter column effecting movement of said diaphragm to open and close said valve, and means in-

cluding a needle valve to effect the predetermined discharge of water from said variable column.

11. A feed water regulator comprising, in combination, a valve, a diaphragm connected with said valve, a water column containing a substantially constant head of water communicating with one side of said diaphragm, a second water column containing a variable head of water and having communication with the other side of said diaphragm, an overflow tube for conducting surplus water from said substantially constant head to said variable head to effect movement of said diaphragm and the valve connected therewith, and variable means cooperating with said overflow tube to effect variations between the heads of water in said columns.

12. A feed water regulator comprising, in combination, a valve, a diaphragm connected with said valve, a water column containing a substantially constant head of water communicating with one side of said diaphragm, a second water column containing a variable head of water having communication with the other side of said diaphragm, and a normally stationary adjustable overflow tube for conducting surplus water from said substantially constant head to said variable head to effect movement of said diaphragm and the valve connected therewith, and means cooperating with said overflow tube to effect a gradual discharge of water from said second water column substantially corresponding with the amount entering through said overflow tube.

13. A feed water regulator comprising, in combination, a valve, a diaphragm connected with said valve, a water column containing a substantially constant head of water communicating with one side of said diaphragm, a second water column containing a variable head of water having communication with the other side of said diaphragm, means including an elongated narrow slot extending from a point near the normal level of water of said substantially constant head to a substantial distance thereabove to effect an increase in the level of water in said variable head commensurate with the increase in the level of said substantially constant head, and means to effect a predetermined gradual lowering of the level of water in said variable head.

14. A feed water regulator comprising, in combination, a valve, a diaphragm connected with said valve, a water column containing a substantially constant head of water communicating with one side of said diaphragm, a second water column containing a variable head of water and having communication with the other side of said diaphragm, an overflow tube for effecting the discharge of surplus water from said substantially constant head into said variable head to ef-

fect movement of said diaphragm and the valve connected therewith, said overflow tube having a restricted discharge orifice for use under normal conditions, and a full discharge orifice to cooperate with said restricted orifice when the water in said constant head is at an abnormal level.

15. A feed water regulator comprising, in combination, a boiler, a feed water pipe therefor, a valve arranged in said pipe to regulate the supply of water to said boiler, a diaphragm connected with said valve, a water column having communication with one side of said diaphragm and with said 10 boiler, a second water column communicating with the other side of said diaphragm, means to maintain a predetermined level of water in the first mentioned water column and said boiler including a tube adapted to 15 effect discharge of water from said first column into said second water column, a valve in said second water column to regulate the escape of water therefrom, and means to convey the water discharged from said second 20 column back to said boiler.

16. A feed water regulator comprising, in combination, a valve, a diaphragm connected with said valve, two water columns adapted respectively to act upon opposite 30 sides of said diaphragm to effect movements of said diaphragm corresponding to variations in the heads of said columns, means to supply equal pressure to both of said columns, and means automatically to provide 35 communication between opposite sides of said diaphragm when the difference in the pressure at said opposite sides reaches a predetermined point.

17. A feed water regulator comprising, in combination, a valve, a diaphragm connected with said valve, two water columns adapted respectively to act upon opposite faces of said diaphragm to effect movements of said diaphragm corresponding with variations in 45 the heads in said columns, means to supply equal pressure to both of said columns, and a relief valve interposed between said columns automatically to provide communication one with the other when the differences 50 in pressures in said columns reach a given point.

18. A feed water regulator comprising, in combination, a valve, a diaphragm connected with said valve, two water columns adapted respectively to act upon opposite sides of said diaphragm to effect movements of said diaphragm corresponding to variations in the heads of said columns, means to supply equal pressure to both of 55 said columns, two bypasses connecting said water columns, a relief valve in one of said bypasses adapted automatically to open when the pressure in one of said columns rises to a predetermined point above 60 the pressure in the other of said columns, a

relief valve in the other of said bypasses adapted automatically to open when the difference in pressures in said two water columns is in the opposite direction to that effecting the first mentioned relief valve 70 whereby said diaphragm will be protected from rupturing during abnormal pressures.

19. A feed water regulator comprising, in combination, a valve, a diaphragm connected with said valve, two water columns adapted 75 respectively to act upon opposite sides of said diaphragm to effect movements of said diaphragm corresponding to variations in the heads of said columns, means to supply equal pressure to both of said columns, and means including two opposed relief valves automatically to provide communication between opposite sides of said diaphragm when the difference in the pressures at said sides reaches a predetermined point. 85

20. In combination, a boiler, means to maintain water at a substantially constant level in said boiler, including a water supply, a valve arranged in said supply, a bellows connected with said valve, a spring cooperating with said bellows tending normally to close said valve, a water column connected with said boiler and having a substantially constant head of water adapted to act against one face of said bellows, a second water column having a variable head of water adapted to act against the opposite face of said bellows, and means to regulate the escape of water from said second water column whereby gradual movement of said 100 valve will be effected.

21. In combination, a boiler, means to maintain the water at a substantially constant level in said boiler including a water supply, a balanced valve for said supply, a bellows connected with said valve, a spring cooperating with said bellows normally to close said valve, a water column having a head adapted to act in opposition to the inherent tension of said bellows and said spring to effect the opening of said valve, a second water column having a relatively smaller head of water adapted to act in cooperation with the pressure exerted by said spring and said diaphragm upon said valve 115 and in opposition to the force exerted thereon by the first mentioned head of water, and means to effect variations in the heads of said columns including an overflow tube for said first mentioned head adapted to discharge into said relatively smaller head and a discharge valve for said variable head. 120

22. In combination, a boiler, means to maintain the water at a substantially constant level in said boiler including a water supply, a balance valve for said supply, a bellows connected with said valve, a spring cooperating with said bellows normally to close said valve, a water column having a head adapted to act in opposition to the 125 130

- inherent tension of said bellows and said spring to effect the opening of said valve, a second water column having a relatively smaller head of water adapted to act in co-operation with the pressure exerted by said spring and said diaphragm upon said valve and in opposition to the force exerted thereon by the first mentioned head of water, and means to effect variations in the heads of said water columns including a needle valve adapted to regulate the discharge of water from said second water column, and means including a steam trap to receive the water discharged through said needle valve, and means to reconvey the water from said trap to said boiler.
23. A liquid feed regulator comprising a liquid supply and means including an elongated discharge opening to automatically effect the gradual regulation of the feeding of said liquid from said supply.
24. A feed water regulator comprising, in combination, a boiler, a feed water pipe therefor, a valve arranged in said pipe to regulate the supply of water to said boiler, a diaphragm connected with said valve, a water column having communication with one side of said diaphragm and with said boiler, a second water column communicating with the other side of said diaphragm, means to maintain a predetermined level of water in the first mentioned water column for said boiler including a tube having a restricted elongated discharge opening adapted to effect discharge of water from said first column into said second column and means to convey the water discharged into said second column back to said boiler.
25. A liquid feed regulator comprising a valve, a diaphragm connected with said valve, two water columns adapted respectively to act upon opposite faces of said diaphragm to effect movements of said diaphragm corresponding with variations in the heads of said columns, means to convey excess water from one of said columns to the other, an adjustable valve to regulate the discharge of water from the last mentioned column, said adjustable valve having a discharge port relatively larger than required for the normal flow of water to insure against clogging by foreign substances discharged from said boiler.
26. In a feed water regulator, a valve, a diaphragm operatively connected with said valve, water columns having communication respectively with opposite sides of said diaphragm arranged to effect the movements of said diaphragm commensurate with variations in the relative heads of water in said columns and means automatically to relieve pressure at opposite sides of said diaphragm to prevent rupturing of said diaphragm.

In testimony whereof, I have signed my name to this specification.

LEONARD D. CHANDLER.
